UNITED STATES PATENT OFFICE

2,145,729

DUPLICATING APPARATUS

Alfred Marchev, La Grange, Ill., assignor to Ditto, Incorporated, Chicago, Ill., a corporation of West Virginia

Application May 29, 1936, Serial No. 82,492

16 Claims. (Cl. 101—132)

The invention relates to duplicating apparatus and is particularly adapted to be embodied in duplicating machines of the type wherein master sheets having data typewritten thereon in reverse are secured to a printing or duplicating drum and are brought into contact with copy sheets which have been previously moistened with a solvent for the ink on the master sheets. However, the invention is limited to this particular use only to the extent indicated in the appended claims.

An object of the invention is to provide a machine of the type described which is simple in construction, inexpensive and efficient.

Another object of the invention is to provide improved means to clamp the master sheets to the duplicating or printing drum.

Other objects and advantages will become apparent as the following description progresses, reference being had to the accompanying drawings, wherein—

Fig. 1 is a plan view of a duplicating machine which embodies the invention.

Fig. 2 is a section taken substantially on line 2—2 of Fig. 1.

Fig. 3 is an enlarged fragmentary section taken on line 3—3 of Fig. 1.

Fig. 4 is an enlarged fragmentary section taken on the same line as Fig. 3 but showing certain parts of the mechanism in changed position.

Fig. 5 is a section taken on line 5—5 of Fig. 3.

Fig. 6 is a section taken on line 6—6 of Fig. 5.

Fig. 7 is an enlarged fragmentary plan view, partly broken away, of the machine.

Fig. 8 is a somewhat diagrammatic section taken on line 8—8 of Fig. 9.

Fig. 9 is a section taken on line 9—9 of Fig. 8.

Fig. 10 is a fragmentary section taken on line 10—10 of Fig. 3, and

Fig. 11 is an enlarged fragmentary section taken on line 11—11 of Fig. 2.

Referring for the present to Figs. 1 to 5, inclusive, it will be noted that the improved duplicating machine comprises two side frames 11 and 12 which are preferably formed from sheet metal and are re-enforced by plates 14 secured to the inner surfaces of the side frames. The side frames are secured to each other by a sheet metal bracket 15 and by several shafts which extend between the side frames.

Disposed between the side frames 11 and 12 is a duplicating or printing drum 17 fixed to a shaft 18 which has its ends journalled in ball bearings 19 mounted in the frames 11 and 12.

(Fig. 5.) The drum 17 comprises a substantially cylindrical wall 21 and end walls 22 and 23. Journalled in the end walls 22 and 23 is a shaft 24 upon which a plurality of clamping or gripper members 25 are pivoted. Pins 26 projecting from the shaft 24 project into slots 27 formed in the gripper members and limit angular displacement of the gripper members relative to the shaft. Springs 28 wound around the shaft 24 yieldingly urge the grippers 25 in a clockwise direction 10 (Fig. 8) relative to the longitudinal axis of the shaft 24. The free ends of the grippers 25 project into a slot 29 formed in the cylindrical wall 21. An inclined surface 30 provided along one edge of the slot 29 co-operates with the free ends of the grippers 25 to clamp master sheets to the drum 17. One of the master sheets is shown in Fig. 8 and is identified by the reference character 31. It will be noted that one edge of the sheet 31 is clamped between the surface 30 and the grippers 25. The end walls of the drum 17 are apertured as at 33 to facilitate the task of assembling the grippers 25 and the shaft 24 with the drum.

Co-operating with the drum 17 to press the copy sheets against the master sheets is a platen roller 35, preferably formed of rubber, the roller 35 being mounted on a shaft 36 which has its ends journalled in ball bearings 38 mounted in arcuate grooves 39 formed in levers 40. The levers 40 are mounted on pins 42 which project from the side frames 11 and 12. The lower ends of the levers 40 are apertured to receive set screws 43 which are adjustably secured to the levers by nuts 44. The heads of the set screws 43 abut against cams 45 fixed to a shaft 46 which is journalled in the side frames 11 and 12 and is provided at one end with a knob 47 so that the shaft 46 may be displaced angularly by the operator. The set screws 43 may be adjusted so that the platen roller 35 exerts the desired pressure upon the copy sheets while they are being pressed against the master sheets. If, at any time the operator desires to change this adjustment it is only necessary to rotate the knob 47 so that the cams 45 will angularly displace the levers 40 in the desired direction to decrease or increase the pressure of the platen roller 35 upon the duplicating drum 17. A tray 50 is provided to receive the 50 copy sheets when they pass from between the duplicating drum 17 and the platen roller 35. The tray is provided with side walls 51, the forward ends of which are slotted as at 52 to engage the pins 42. Intermediate its ends, the tray 50 55

rests upon lugs 55 projecting from the frames 11 and 12.

The means for feeding copy sheets to the duplicating drum 17 and the platen roller 35 preferably comprises a roller 57 formed of rubber and mounted on a shaft 58. The cylindrical surface of the roller is preferably corrugated as indicated at 59. Disposed above the roller 57 is a composition roller 60 mounted on a shaft 61, the roller 60 being formed of a composition which is substantially non-absorbent.

The shaft 58 has its ends journalled in bearing rings 63 which are mounted in arcuate recesses provided in one end of each of two levers 64, the levers 64 being journalled on a shaft 65 which extends between the side frames 11 and 12. The other ends of the levers 64 are provided with a plurality of notches 66. Engaging a notch 66 in each of the levers 64 is one end of one of a plurality of springs 67 which have their other ends secured to pins 68 projecting from the side frames 11 and 12. Obviously, the springs 67 yieldingly urge the roller 57 against the composition roller 60 and the pressure with which the roller 57 is urged against the composition roller 60 may be adjusted by selecting one or another of the notches 66 in each lever 64 as the point to which the associated spring 67 should be attached.

30 The shaft 61 has a recess 70 in each end (Fig. 10). A bushing 71 disposed in the recess is journalled on one end of a pin 72 projecting from the adjacent side frame 11 or 12, the bearing portion of the pin being of reduced diameter. The pin 35 is secured to the adjacent side frame by a block 74 secured to the side frame by screws 75. Fixed to the blocks 74 and extending between them is a guide plate 77 which prevents the copy sheets from being drawn around the composition roller 40 60. At one end of the shaft 61 a gear 78 is secured (Fig. 2). The gear 78 meshes with a pinion 79 which meshes, in turn, with a gear 80 mounted upon one end of the shaft 18 and constrained to rotate with the drum 17 by pins 81 45 (Fig. 5). The pins 81 also project through a gear 83 mounted upon the shaft 18. The gear 83 meshes with a pinion 85 fixed to one end of a shaft 86 which is journalled in a bearing 87 secured in the side frame 12. The outer end of the shaft 86 has a crank arm or lever 88 secured thereto whereby the operator may rotate the shaft 86 so that the pinion 85 will rotate the gear 83 and the drum 17. Obviously, when the drum 17 is 50 rotated, the gear 80 will drive the pinion 79 and it, in turn, will drive the gear 78 which drives the composition roller 60. The roller 57 frictionally engages the composition roller 60 and therefore will be driven in unison with the composition roller 60.

60 Secured to the end wall 22 of the drum 17 by bolts 90 is a cam 91 which has a dwell 92. The dwell 92 is a portion of a cylindrical surface having its longitudinal axis coincident with the axis of rotation of the shaft 18. The dwell 92 is only 65 interrupted by a single depression 94. Co-operating with the cam 91 is a roller 96 adapted to ride upon the dwell 92 and to drop into the depression 94 when the depression is aligned with the roller. The roller is mounted on one end of a lever 95 which is pivoted intermediate its ends on a stub shaft 98 projecting from the side frame 11. The other end of the lever 95 is engageable with a lever 97 which is also pivoted upon the stub shaft 98. The roller 96 is urged against the 70 cam 91 by a compression spring 99, one end of

which spring bears against the lever 95 and the other end of the spring bears against a bracket 100 fixed to the inner side of the reinforcing plate 14 provided for the side frame 12. In Fig. 2, the roller 96 is shown resting in the depression 94. It 5 will be readily understood that when the shaft 18 is rotated in a counter-clockwise direction the roller 96 will ride up on the dwell 92 and will displace the lever 95 in a clockwise direction (Fig. 2) against the action of the spring 99 and the 10 lever 95 will displace the lever 97 angularly in a clockwise direction (Fig. 2). The lever 97 actuates means for supplying a solvent to means for moistening the copy sheets as they are advanced to the composition roller 60 and the roller 57, 15 these rollers being feed rollers to feed the copy sheets between the drum 17 and the platen roller 35. The solvent supplying means preferably comprises a tank or reservoir 102 disposed adjacent the sheet metal bracket 15. Extending 20 through the reservoir 102 is a cylindrical member 103 having a central bore 104 which is closed at its lower end. The cylindrical member 103 is of reduced diameter at its lower end, the reduced portion projecting through the bracket 15 and 25 being secured thereto by a nut 105. Ports 106 in a cylindrical member 103 permit the bore 104 to communicate with the interior of the reservoir in the bottom portion thereof. Ports 107 in the cylindrical member 103 permit the bore 104 to 30 communicate with the interior of the reservoir 102 in the upper portion thereof. Slidably journalled in the lower end of the bore 104 is a piston 110 which is connected to the free end of the lever 97 by a piston rod 111. It will be noted that the 35 rod 111 projects through a bushing 113 which closes the upper end of the bore 104. Nuts 115 screw-threaded upon the upper end of the piston rod 111 rest upon an arcuate surface 116 provided upon the lever 97. Obviously, the nuts 115 40 can be manipulated to bring the piston 110 into adjusted positions with respect to the lever 97. A spring 118 disposed in the bore 104 extends between the bushing 113 and the piston 110 and urges the piston downwardly. Obviously, when 45 the lever 97 is displaced in a clockwise direction (Fig. 2) as described above, the piston 110 will be drawn upwardly. The construction is such that the piston will be drawn above the ports 106 so that the solvent may flow from the interior 50 of the reservoir 102 through the ports 106 and into the lower end of the bore 104. Then when the roller 96 again drops into the depression 94, the spring 118 will drive the piston 110 downwardly to drive the solvent from the lower end of the bore 104 into a tube 120 which 55 communicates with the bottom end of the bore 104. The tube 120 has one end seated in a sleeve 121. Disposed in the sleeve 121 is a ball 122 which operates with the adjacent end of the tube 120 60 and with a spring 124 to form a check valve which prevents the solvent from flowing from the sleeve 121 back through the tube 120 to the bore 104. The sleeve 121 communicates through a tube 127 with the means for applying the solvent to the 65 copy sheets.

Secured to the lever 97 by screws 130 is an arm 131 provided with a roller 133 which rides upon a cam 134, the cam 134 being fixed to a shaft 135 journalled in the side frames 11 and 12. 70 The cam 134 may be rotated from the position wherein it is shown in Fig. 2 to another position to lift the roller 133 and the arm 131 so that the lever 97 will be displaced angularly in a clockwise direction (Fig. 2). The lever 97 will then 75

not rest upon one end of the lever 86 when the roller 86 is in the depression 94 and the piston 110 will be lifted from the position wherein it is shown in Fig. 2. Then when the machine is operated and the piston is raised and lowered alternately, its strokes will be shortened and a smaller amount of solvent will be delivered for each cycle of operations to the tube 120. The cam 134 has a gradual rise or increase in radius so that the 10 amount of solvent delivered to the tube 120 can be adjusted accurately.

The upper end of the tube 127 communicates with a chamber 148 which communicates with the atmosphere from a short tube 141 (Fig. 2). 15 Communicating with the lower end of the chamber 148 is a tube 142. The tube 142 communicates with a chamber 144 provided in a housing 145 having a cover plate 146, the flow of solvent from the tube 142 to the chamber 144 being controlled by a valve mechanism designated generally by the reference character 147. Disposed in the lower portion of the chamber 144 is a felt pad 149, one end of which contacts a felt strip 150 having a fold 151 and a substantially 20 vertically extending portion 152. Any solvent collecting in the lower portion of the chamber 144 drains back into the reservoir 102 through a tube 154. The folded portion 151 of the felt strip 150 engages the composition roller 60 and transfers the solvent from the chamber to the composition roller 60. When the copy sheets pass between the composition roller 60 and the roller 57 the upper faces of the copy sheets are moistened with the solvent, which solvent is preferably alcohol with or without other liquid solvents. The 25 housing 145 is urged yieldingly toward the composition roller 60 so that the folded portion 151 of the felt strip 150 will constantly engage the composition roller. The housing 145, the valve mechanism 147, the felt pad 149, the felt strip 150 and the mechanism mounting the housing 145 in the manner described in detail in the co-pending application, S. N. 58,522, filed January 10, 1936, by Stephen 30 Kokay and therefore this construction need not be described in detail in this application.

When the machine is to be placed in operation, the copy sheets are preferably placed upon a feed table 160 which has downwardly extending side flanges 161 (Figs. 2 and 11). Secured to the side frames 11 and 12 are Z-shaped brackets 163 which have laterally extending lugs 164 at their forward edges. Slots 166 formed in the Z-shaped brackets 163 are adapted to receive bars 167 fastened to the outer sides of the flanges 161, the construction being such that the table 160 is simply displaced toward the machine with the bars 167 in horizontal alignment with the slots 166 until the bars engage the ends of the slots 166 as illustrated in Fig. 2. Extending between the side frames 11 and 12 is a rod 170 which is engageable by notches 171 formed in levers 173 which are pivoted intermediate their ends on pins 174 projecting from the flanges 161. A notch 171 is formed in one end of each of the levers 173 and it will be noted that the other ends of the levers engage the bottom surface of the table 160 when the notches 171 are engaged by the rod 170. Intermediate the notches 171 and the pins 174, the levers 173 are provided with finger pieces 175 which may be pressed upwardly by the operator to disengage the notches 171 from the rod 170 when the operator desires to remove the table 160 from the machine.

75 L-shaped guide members 188 are mounted ad-

justably on the top surface of the table 160 (Figs. 1 and 2). The guide members have downwardly projecting pins 181 which ride in slots 182 provided in the table 160. Springs 183 wound around the pins 181 cause the bottom surfaces of the guides 188 to engage the top surface of the table 160 with sufficient pressure so that the guide members will not be displaced accidentally but must be displaced by the operator. Obviously, the guide members may be adjusted to 10 align the copy sheets with the master on the drum 17.

As best shown in Figs. 2, 3 and 4, the forward end of the table 160 is provided with an inclined portion 187 which terminates adjacent the junction point between the composition roller 60 and its co-operating roller 57. This construction insures that the copy sheets will be advanced properly to these feed rollers. It is understood, of course, that the feed rollers 60 and 57 advance 15 the copy sheets to the junction between the duplicating drum 17 and the platen roller 35 and that the copy sheets pass between the drum 17 and the platen roller 35.

In Fig. 3, the drum 17 is in the position in which a master sheet 31 clamped to it is in registry with the remaining mechanism of the machine so that when a copy sheet is then advanced by the feed rollers 60 and 57 and the machine is operated by rotating the crank arm 88, the copy sheet will 20 come into registry with the master sheet and the data on the master sheet will leave a corresponding impression upon the copy sheet. It will be noted that in Fig. 3, the roller 96 engages the depression 94. Assuming that the operator has a 25 stack of copy sheets on the feed table 160 and is operating the machine, it will be readily understood that the operator will feel each time the roller 96 drops into the depression 94 and will permit the machine to come to a complete stop 30 until a copy sheet has been advanced to the feed rolls so that when the machine is again set in operation, the feed rolls will advance the copy sheet to have it register with the master sheet.

To one end of the shaft 24 which carries the grippers 25, a lever 200 is pinned intermediate its ends. One end of the lever 200 is provided with a pin 201 to which one end of a tension spring 202 is secured, the other end of the spring 202 being secured to a pin 203 projecting from a lug 204 formed integral with the drum 17. The other end of the lever 200 is engageable by the free end of a lever 205 which is pivoted on a pin 206 projecting from the frame 11. A slot 207 formed in the free end of the lever 205 accommodates a pin 208 fixed to a hand lever 210 which is pivoted on a pin 211 projecting from the frame 11. The hand lever 210 is provided with a handle member 213. When the parts described in the preceding paragraph are in the positions in which they are 35 illustrated in Fig. 3, the lever 200 is not in the vicinity of the lever 205 and therefore is not engageable with it. This is the position of the various parts when the roller 96 rests in the depression 94. However, when it is desired to replace the master sheet 31 with a new master sheet 31, the drum is rotated so that a slot 215 formed in one edge of the cylindrical wall 21 of the drum 17 registers with a roller 217 journalled on a pin 218 which projects from the lever 205. The operator then holds the crank member 88 stationary and displaces the hand lever 210 from the position wherein it is shown in Fig. 3 to the position wherein it is shown in Fig. 4 so that the lever 205 40 displaces the roller 217 into the slot 215 and the 45 50 55 60 65 70 75 80 85 90 95 100 105 110 115 120 125 130 135 140 145 150 155 160 165 170 175 180 185 190 195 200 205 210 215 220 225 230 drum 17 is held against rotation. Simultaneously with the movement of the roller 217 into the slot 215, the lever 205 engages the lever 200 and displaces it from the position wherein it is shown in Fig. 3 to the position wherein it is shown in Fig. 4 so that the shaft 24 is displaced angularly in a counter-clockwise direction (Fig. 4). When the shaft 24 is displaced in this direction, the grippers 25 are displaced from the position wherein they are shown in Fig. 3 to the position wherein they are shown in Fig. 4 so that the old master sheet 31 is released. The operator then removes the old master sheet and replaces it with a new one, whereupon the lever 213 is returned to the position wherein it is shown in Fig. 3 so that the spring 202 will displace the lever 200, the shaft 24 and the grippers 25 in a clockwise direction (Fig. 4) to clamp the new master sheet in place upon the drum. The machine is then ready for use and copy sheets may be fed to the feed rolls one by one to obtain copies of the data on the master sheet.

The operation of the machine is apparent from the above description. Briefly, a master sheet is made by placing a sheet of paper in a typewriter with a carbon sheet against the back surface of the sheet of paper. The datum is then typewritten upon the sheet of paper and it appears in reverse on the rear side of the paper. The master sheet is then clamped on the drum 17 with the writing in reverse facing outwards. The solvent employed is one which will dissolve the carbon. The copy sheets are fed through the machine as described above, each copy sheet being moistened on the side which comes into contact with the master sheet. A small amount of carbon is dissolved each time a copy sheet is fed through the machine and each copy sheet is a clear copy of the original.

40 The roller 57 has a corrugated outer surface as described above. This insures that there will be a rapid evaporation of any excess solvent which is deposited upon the roller 57 by the roller 60.

Referring to Fig. 4 it will be noted that when the lever 210 is in position wherein it is shown in Fig. 4, the pin 209 is positioned with respect to the pin 211 and the point of contact between the levers 205 and 200 so that the lever 210 will remain in the position wherein it is shown until the operator grasps the handle 213 and displaces the lever 210 in a counter-clockwise direction (Fig. 4) against the action of the spring 202.

While I have shown and described certain embodiments of my invention, it is to be understood that it is capable of many modifications. Changes, therefore in the construction and arrangement may be made without departing from the spirit and scope of the invention as disclosed in the appended claims, in which it is my intention to claim all novelty inherent in my invention as broadly as possible, in view of the prior art.

I claim:

1. A duplicating machine comprising a duplicating drum, means carried by the drum to clamp a master sheet thereon, means for locking the drum against rotation, means operable while the drum is stationary for releasing said clamping means, and common means for actuating said locking means and said releasing means.

2. A duplicating machine comprising a frame, a rotatable duplicating drum mounted in said frame, means carried by said drum for clamping a master sheet thereto, means movably mounted on said frame to engage said drum and lock it

against rotation, said last-mentioned means being operable to release said clamping means while the drum is stationary, and a lever pivoted on said frame for actuating said locking means.

3. A duplicating machine comprising a frame, a rotatable duplicating drum mounted in said frame, means carried by said drum for clamping a master sheet thereto, a lever pivoted on said frame to lock said drum against rotation and to release said clamping means, and a second lever pivoted on said frame for actuating the first-mentioned lever.

4. A duplicating machine comprising a frame, a rotatable duplicating drum mounted in said frame, means carried by said drum for clamping a master sheet thereto, a lever pivoted on said frame to lock said drum against rotation and to release said clamping means, and means on said frame having a lost motion connection with said lever for actuating said lever.

5. A duplicating machine comprising a frame, a rotatable duplicating drum mounted in said frame, a shaft pivoted in said drum and carrying means for clamping a master sheet to said drum, a lever fixed to said shaft, a spring yieldably urging said shaft into a position wherein the clamping means will clamp a master sheet to the drum, a second lever pivoted to said frame and engageable with the first-mentioned lever to displace it and release said clamping means against the action of said spring, said second lever having means engageable with said drum to hold it against rotation, and a third lever pivoted to said frame for actuating said second lever.

6. A duplicating machine comprising a frame, a rotatable duplicating drum having a recess formed therein, a shaft pivoted in said drum, means carried by said shaft for clamping a master sheet to said drum, a lever fixed to said shaft, a spring yieldably urging said shaft into a position wherein the clamping means will clamp a master sheet to the drum, a second lever pivoted to said frame and engageable with the first-mentioned lever to displace it and release said clamping means against the action of said spring, said second lever having means engageable with said recess to hold the drum against rotation, and means movably mounted on said frame for actuating said second lever.

7. A duplicating machine comprising a frame, a rotatable duplicating drum mounted in said frame, means carried by said drum for clamping a master sheet thereto, manually operable means mounted on said frame for releasing said clamping means, a platen roller co-operating with said drum, means for moistening copy sheets advanced to said drum and said platen roller, a cam constrained to rotate with said drum, a roller riding on said cam, said cam and said roller co-operating to indicate to the operator when said drum is in the proper position to have a copy sheet advanced thereto, and means actuated by said roller for controlling the supply of solvent to said moistening means.

8. A duplicating machine comprising a frame, a rotatable duplicating drum mounted in said frame, means carried by said drum for clamping a master sheet thereto, and means movably mounted in said frame and operable while the drum is stationary in one position to lock said drum against rotation and release said clamping means.

9. A duplicating machine comprising a frame, a rotatable duplicating drum mounted in said frame, means carried by said drum for clamping

a master sheet thereto, and means in said frame to lock said drum against rotation and to release said clamping means while the drum is locked against rotation, said locking and releasing means comprising a lever pivoted on said frame and manually operable to actuate said locking and releasing means.

10. A duplicating machine comprising a frame, a rotatable duplicating drum mounted in said frame, a platen roller co-operating with said duplicating drum to press copy sheets against it, means carried by said drum for clamping a master sheet thereto, and means movably mounted on said frame movable into position to release said clamping means when said drum is brought to a stop and held stationary with said clamping means in registry with said movably mounted means.

11. A duplicating machine comprising a frame, a rotatable duplicating drum mounted in said frame, a platen roller co-operating with said duplicating drum to press copy sheets against it, means carried by said drum for clamping a master sheet thereto, and manually operable means movably mounted on said frame movable into position to release said clamping means when said drum is brought to a stop and held stationary with said clamping means in registry with said movably mounted means.

30 12. A duplicating machine comprising a frame, a rotatable duplicating drum mounted in said frame, a platen roller co-operating with said duplicating drum to press copy sheets against it, means carried by said drum for clamping a master sheet thereto, and a lever pivotally mounted on said frame and movable into position to release said clamping means when said drum is brought to a stop with said clamping means in registry with said movably mounted means.

40 13. A duplicating machine comprising a frame, a rotatable duplicating drum mounted in said frame, a platen roller co-operating with said duplicating drum to press the copy sheets against it, a shaft pivotally mounted in said drum, clamping means mounted on said shaft for clamping

a master sheet to said drum, a lever secured to said shaft and a second lever mounted on said frame for displacing the first-mentioned lever to release the clamping means when the drum is brought to a stop and held stationary with the 5 first-mentioned lever in registry with said second lever.

14. A duplicating machine comprising a frame, a rotatable duplicating drum mounted in said frame, a shaft pivoted in said drum and carrying 10 means for clamping a master sheet to said drum, a lever fixed to said shaft, a spring yieldably urging said shaft into a position wherein the clamping means will clamp a master sheet to the drum, a second lever pivoted to said frame 15 and engageable with the first-mentioned lever to displace it and release said clamping means against the action of said spring, said secnd lever having means engageable with said drum to hold it against rotation.

20 15. A duplicating machine comprising a frame, a rotatable duplicating drum mounted in said frame, means carried by said drum for clamping a master sheet thereto, stop means on said drum, a lever pivoted on said frame and having means 25 engageable with said stop means to lock said drum against rotation in either direction, said lever having means to release said clamping means while the drum is held stationary, and means on said frame having a lost motion connection with said lever for actuating said lever.

30 16. A duplicating machine comprising a frame, a rotatable duplicating drum mounted in said frame, means carried by said drum for securing a master sheet thereto, means movably mounted 35 on said frame to engage said drum and hold it against rotation, said means including a mechanism cooperating with said master sheet securing means to release the master sheet while the drum is held by said means and adapted when the 40 drum is released for renewed rotation to move said master sheet securing means automatically to its operative gripping position.

ALFRED MARCHEV. 45
